ALTERNATING CURRENT SYNCHRONIZING APPARATUS

Maurice Toussaint, Paris, France, assignor to Societe Francaise Radio Electrique, a corporation of France

Application August 31, 1946, Serial No. 694,405
In France June 2, 1945Section 1, Public Law 690, August 8, 1946
Patent expires June 2, 1965

6 Claims. (Cl. 322—36)

1

This invention relates to alternating current synchronising apparatus and has for its object to provide an arrangement which will automatically synchronise two frequencies.

An arrangement in accordance with this invention makes use of a cathode ray phasemeter, of a type known per se whose spot remains stationary if the two frequencies are synchronised but describes slowly an arc of a circle when the relative phase changes.

The invention is illustrated in and explained in connection with the accompanying drawings in which Fig. 1 is a general schematic diagram of the phasemeter and associated automatic synchronising arrangement; Figs. 2, 3 and 4 are explanatory graphical figures relating to the operation of the arrangement of Fig. 1; and Fig. 5 is a schematic representation of a preferred form of ratchet driven reverser employed in the synchronising arrangement.

Referring to Fig. 1 suppose F and F' are two frequencies to be maintained in synchronism, F being for example, the master frequency and F' being a secondary or slave frequency to be synchronised with it. The frequency F' is split into two quadrature components which are applied with equal amplitude to the mutually perpendicular pairs of deflecting plates of a cathode ray tube one component to each pair. This quadrature application will of course cause the cathode ray to trace a circular path on the screen. In Fig. 1 the two equal amplitude quadrature components of frequency F' are provided by the slave generator 3, one being applied directly and the other being applied through a suitable 90° phase shifter 4. The control electrode of the tube is biassed so that the electron beam is normally cut off. The cut-off bias on the control electrode is overcome periodically for a very brief impulse in each cycle by alternating voltage applied from a generator 2 or other source of the master frequency F , so that the beam appears during this short portion of each cycle of frequency F and the spot on the screen traces an arc of a few degrees during a fraction of the period $1/F$, the fraction being determined by the amplitude and wave form of the voltage applied to the control electrode from 2. By reason of the phenomenon of persistence of vision there appears on the screen a trace in the form of a small arc—which arc is reduced practically to a spot by the use of a suitable wave form from 2—which remains stationary if the frequencies F and F' are absolutely in synchronism but which moves in one direction or the other with an angular speed equal to

2 $\pi(F-F')$ if the frequencies are not synchronised.

The phase meter indications above described could, of course, be utilised by an observer controlling manually the frequency of the slave generator 3 until the spot appeared stationary. The present invention has for its object to provide an automatic arrangement which will provide the necessary control for synchronising without needing visual observation and manual control.

10 To this end in accordance with the invention there is provided adjacent and parallel to the screen of the tube an opaque circular disc 5 having a circular aperture 6 whose diameter is sensibly larger than the length of the spot on the screen and whose radial distance from the centre of the disc is substantially equal to the radius of the circular path of the spot on the screen, the disc and screen being co-axial. Behind the aperture in the disc is a mirror reflector 7 fast with 15 the disc and serving to reflect the image of the spot on to an axially arranged photo-electrical cell 8.

The disc 5 is driven by a reversible electric motor 12 through step-down gearing 13 giving a 20 considerable gear ratio. When the spot on the screen is opposite the aperture the photoelectric cell is illuminated and controls through a suitable 25 amplifier 9, and a relay 10 (an electro-mechanical system 11 (which will be later described herein) whereby the reversal of the motor 12 is controlled.

As will be seen more clearly later if the spot 30 remains stationary on the screen of the cathode ray tube the disc 5 will describe alternately equal angles slightly inferior to 360° in both directions of rotation. If the angles of rotation α of the disc be plotted as ordinates against time t , this condition is as represented by the toothed curve of Fig. 2.

If, however, by reason of lack of synchronism 35 between F and F' the spot has itself a slow movement of rotation (much slower than that of the disc) the duration of rotation of the disc in the direction of spot rotation will be longer than in the opposite sense. This condition is as represented by the curve of Fig. 3 where the angles of rotation α are again plotted against time t . To simplify explanation the graph of this figure has been drawn on the assumption—made purely for convenience and as an example—that the spot 40 moves with an angular speed equal to one-third of the speed of rotation of the disc 3, the spot and aperture 6 being in coincidence at the origin of the graph.

On this assumption the first coincidence (after the origin) between the spot and aperture will

occur when the disc has turned through an angle $+3\pi$; the next (after reversal of the sense of rotation of the disc) will occur when the disc has turned in this opposite direction for an angle of

$$\frac{-3\pi}{2}$$

and this cycle of operations will repeat itself periodically with a period equal to 2.25θ , θ being the corresponding period when the spot is stationary.

The arrangement is accordingly utilised to secure automatic synchronisation of the two generators (2, 3) by controlling the speed of a shaft 15 of the generator 3 through a suitable reduction gear 14 from the motor 12, this shaft control operating as suitable frequency varying device of known type to vary the frequency of the generator 3 in the direction required to annul any lack of synchronism. Any difference between the angle turned by the disc in one direction and that turned in the other will thus tend to diminish the lack of synchronism until proper synchronism is re-established. The resultant angle through which the disc will have turned finally before synchronism is established will be equal to that which would have been necessary for manual control to bring the two generators to synchronism taking into account of course the gear ratio involved. Figure 4 represents for example fluctuations of the angle α in the interval of time which occurs between the departure from synchronism and re-establishment; during this interval the angle through which the disc will have turned is 5π in the example chosen.

The above described arrangement will work satisfactorily if the natural stability of the two generators is inherently sufficiently good to ensure that rapid and important changes of frequency will not occur. In practice the speed of rotation of the disc is chosen in such a manner that in the course of one period of rotation thereof the maximum phase difference likely to occur between the two frequencies does not exceed about $\frac{1}{10}$ of this period. The arrangement above described has the minor defect that a very small variation of the order of $1/100$ of this period can occur in the frequency of the slave generator. This defect, however, may be easily avoided by providing a little play in the control arrangement for the slave generator, e. g. by using a known type of drive such as that employed in the cinema.

The automatic reversal of the direction of rotation of the motor 12, Fig. 1 is effected by a reverser 11 controlled by the amplifier 9. Referring to Fig. 5 which shows a preferred form for the reverser 11 this comprises a commutator having an insulating shaft on which is a conductive sleeve 24 cut away by a double series of insulating spaces 25. With this commutator are associated brushes 16, 17, 18 which serve with the commutator as a reversing switch and through which the motor 12 is energised. The commutator is driven by a ratchet wheel 19 and the arrangement of the insulating spaces 25 and of the teeth of the wheel 19 are such that displacement from one tooth to the next causes a reversal of the motor. Control of the ratchet wheel is effected by an electro-magnet 23 excited by current controlled by the relay 10 (see Fig. 1), in the output circuit of the amplifier 9. This electro-magnet acts on an armature 22 pivoted on an axis 0 and having an abutment K operating against a stop (not shown) to limit the return action of the spring 21. The

armature 22 drives the ratchet wheel 19 through the striker member 20.

The invention has many applications notably to radio diffusion networks for the control of stations therein in accordance with a central control frequency fed either over lines or pilot or other radio transmission or in any other way.

What I claim is:

1. A system for automatically synchronizing the frequency of master and slave generators supplying periodic wave outputs comprising in combination, a cathode ray oscillograph having a screen and electrode means and means applying to said electrode means wave energies from said generators to produce on the screen a small arcuate luminous spot related in length to the period of the output wave of the master generator and, under conditions of non-synchronism, having apparent motion whose speed is proportional to, and in one or the opposite direction dependent on the sign of, the inequality of the frequencies, a disk parallel to the screen having a circular aperture slightly larger than the spot and at a radial distance substantially equal to the radial distance of the spot on the screen and coaxial therewith, means for rotating the disk about its axis, a photoelectric cell and its circuit, said cell being positioned to receive light reflected from said spot during rotation of the disk, light reflecting means for reflecting the light of the spot emerging through said aperture onto said cell, and means controlled by said circuit for bringing the slave generator into synchronism with the master generator.

2. A system according to claim 1 including means for normally applying to one electrode a potential to block the cathode ray, and in which the means for applying wave energies from the generators applies the wave of the master oscillator during a fraction of its period to said one electrode to unblock the cathode ray and the wave from the other oscillator to other electrodes to cause rotation of the spot in a circumference having said radial distance.

3. A system according to claim 1 in which the means for rotating the disk includes a reverser to alternate the sense of rotation at the respective operations of the photoelectric cell circuit.

4. A system according to claim 1 in which the means for rotating the disk includes a driving motor and a reverser, said reverser including a commutator, a step-by-step ratchet for driving the commutator and electromagnetic means under control of the cell for stepping the commutator.

5. A system according to claim 1 in which the means for bringing the slave generator into synchronism, includes a driving means having sufficient play to prevent any control action being applied until a predetermined small departure from synchronism occurs.

6. In combination, in a system for automatically maintaining synchronization between a voltage of stabilized frequency and a voltage servient to said stabilized frequency but whose phase tends to vary slowly as a function of time, a cathode ray tube having a Wehnelt electrode negatively polarized so as to block the tube, means for unblocking the tube at said stabilized frequency to cause a luminous spot to appear periodically on the screen of the tube, two pairs of deflection plates in space quadrature and means for impressing equal voltages in phase quadrature at the servient frequency on said pairs of plates so as to produce a displacement of the spot along a circumference, a disk on the same axis as that of said circumference hav-

75

ing an aperture located at a distance from the center of the disk equal to the radius of the circumference, a mirror, a motor for driving the sub-disk, by means of a reduction gear at a speed substantially above that of the spot, a photoelectric cell located along said axis so as to be excited from the image reflected by the mirror when the aperture of the disk passes in front of the spot, a relay controlled by the cell and adapted to control rotation of the motor for each successive excitation, alternatively in one direction and in the other, and control means for the servient frequency comprising elements controlled by rotation of the motor through a reduction gear, said reduction being chosen in consideration of the time constant of the control means so that a rotation of the disk of 360° in the same direction is

10 insufficient to reduce in any appreciable manner at existing difference between the two frequencies, but such that this difference is suppressed by an accumulation of the average effects when the algebraic sum of the angles transversed by the disk in one sense and in the other attains a predetermined value.
